Des. 186,185
Patented Sept. 22, 1959

186,185

OVERHEAD LIGHTING WARE LENS

Warren O. Benjamin, Corning, N.Y., assignor to Corning
Glass Works, Corning, N.Y., a corporation of New
York

Application April 24, 1958, Serial No. 50,598

Term of patent 14 years

(Cl. D48—16)

Fig. 1

Fig. 2

Fig. 3

Fig. 1 is a top plan view of an overhead lighting ware lens embodying my new design.

Fig. 2 is a sectional view taken on line 2—2 of Fig. 1.

Fig. 3 is a fragmentary sectional view, on an enlarged scale, taken on line 3—3 of Fig. 1.

Fig. 4 is a bottom plan view of the lens.

Fig. 5 is a sectional view taken on line 5—5 of Fig. 3.

I claim:

The ornamental design for an overhead lighting ware lens, as shown.
